UNITED STATES PATENT OFFICE.

WALTER C. READ, OF NEWARK, NEW JERSEY.

HOLDING DEVICE FOR BRUSH-BLANKS.

SPECIFICATION forming part of Letters Patent No. 660,589, dated October 30, 1900.

Application filed May 25, 1899. Serial No. 718,273. (No model.)

To all whom it may concern:

Be it known that I, WALTER C. READ, a citizen of the United States, residing at Newark, in the State of New Jersey, have invented 5
5 Improvements in Holding Devices for Brush-Blanks, of which the following is a specification.

My invention relates to holding devices for brushes and the like, and is intended to co- 10 operate with a trimmer or cutter which is adapted normally to trim or cut brushes to a flat surface, the special purposes of the improvement being to provide means whereby the cutting or trimming machine may be used 15 for trimming brushes to a curved face.

In the accompanying drawings, Figure 1 represents the invention in perspective as applied to a cutting machine having straight-edged cutters which are adapted to cut flat 20 faces on the blank. Fig. 2 is an enlarged view of the improvement detached from the machine, and Fig. 3 is a view similar to Fig. 2 of a modification.

The cutting-machine may be of any ordinary type comprising a standard A and rotary cutters B, which are adapted to cut or trim flat faces on the brush. At one end of the table standards a extend vertically, and these carry a bracket 1 made up of arms 2 25 and a cross-bar b', the said arms being held by collars 3 adjustably secured to the standard a by thumb-screws 4. The cross-bar b' carries a hanger j, through which a rod c extends, being supported adjustably by a collar 30 5, resting upon the hanger j and secured to the rod by a thumb-screw 6. The rod c carries at its lower end a bearing, through which a bar f extends, and this bar has sleeves g at its ends, through which extend vertically the 35 5 rods E, to the lower ends of which a brush-holder d is secured. The vertical position of the rods E is determined and fixed by nuts h engaging screw-threads on the rods above and below the sleeves g. The brush-holder 40 45 may be of any ordinary form, having suitable clamping means to hold the brush directly over the cutters, as shown in Fig. 1. The bar f has rocking movement in the bearing i, so that by moving the brush-holder laterally it

will swing in the arc of a circle, of which the 50 axis of the rod f is the center, and thus a laterally-curved face may be given to the brush-blank. The hanger j is loosely journaled upon the cross-bar b' of the bracket 1, and as this cross-bar extends in a plane at right angles to the plane of the rocking bar f the brush-holder may be given a swinging movement from front to rear, so as to describe an 55 arc the center of which will be the axis of the hanger j. From this construction it will be 60 seen that a curved face may be formed on the brush both laterally and longitudinally.

In Fig. 3 is shown a modification which relates more particularly to the form of the supporting-bracket, this consisting in this instance of converging arms 2, having a hanger j" at the meeting-point of the arms, from which the support for the holder is hung. In this form the bar f not only has rocking movement to present the brush-blank laterally to 65 the cutters in the arc of a circle, but the bar f may slide longitudinally in the bearing i, so that all parts of the brush-blank may be brought over the knife by sliding the bar f in the bearing i. In this form the brush will 70 be cut on a curve in one direction only, and the rounded surface of the blank will form a 75 portion of a cylinder.

I claim as my invention—

1. In combination, the standards, the 80 bracket vertically adjustable thereon, and the holder suspended from said bracket and capable of having a longitudinal reciprocating movement and a transverse swinging movement, substantially as described. 85

2. In combination, the standards, the bracket, the bearing suspended from said bracket and the holder having a rod slidably and rotatably mounted in said bearing whereby said holder may be reciprocated 90 longitudinally and swing transversely in the arc of a circle, substantially as described.

3. In combination, the holder, the bearing i, the rod f turning therein, means connecting the rod with the holder, the rod b' extending in a plane at right angles to the rod f, the hanger j' turning about the rod b', the vertically-extending rod c held by the hanger j'

and connected at its lower end to the bearing *i*, substantially as described.

4. In combination, the brush - holder, the bearing *i*, the rod *f* journaled therein and connected with the holder, the rod *c* extending upwardly from the bearing *i*, the hanger *j* for holding the rod *c*, the cross-rod *b'* about which the hanger may turn, the adjustable

arms 2 and the standards *a* to which the arms are secured, substantially as described.

In witness whereof I have hereunto set my hand in presence of two witnesses.

WALTER C. READ.
